UNITED STATES PATENT OFFICE

117,124

DESIGN FOR A HEATER

Carl E. Meyerhoefer, Brooklyn, N. Y., assignor to
E. A. Laboratories, Inc., Brooklyn, N. Y., a corporation of New York

Application July 20, 1939, Serial No. 86,096

Term of patent 7 years

To all whom it may concern:

Be it known that I, Carl E. Meyerhoefer, a citizen of Germany, residing at Brooklyn, in the county of Kings and State of New York, have invented a new, original, and ornamental Design for a Vehicle Heater, of which the following is a specification, reference being had to the accompanying drawing, forming a part thereof, wherein:

Fig. 1 is a top plan view of a vehicle heater showing my new design;

Fig. 2 is a front elevation; and

Fig. 3 is a side view thereof.

The rear portion of the heater presents merely a plain surface having the medial band or beading extending across the same as shown in the preceding figures. The side opposite to that shown in Fig. 3 corresponds substantially to the latter illustration excepting that the outlet member is omitted.

I claim:

The ornamental design for a vehicle heater, as shown and described.

CARL E. MEYERHOEFER.
